Attorney

UNITED STATES PATENT OFFICE

WARD M. JONES, OF DETROIT, MICHIGAN

AIR CONDITIONING APPARATUS

Application filed July 29, 1931. Serial No. 553,839.

The present invention relates to air-conditioning apparatus, and more particularly to a novel form of flue adapted to be associated with gas heater ranges and the like. One object of the present invention is the provision of improved means whereby the gases escaping from the flue of a gas range may be substantially freed from such foreign substances as soot, grease and the like. Another object of the invention is to provide apparatus of the character designated containing a liquid purifying agent.

These and other objects of the invention will be apparent from the following specification, wherein a preferred and illustrative embodiment of the invention has been selected, for the purposes of description.

In the accompanying drawings:

Fig. 1 is a perspective view of a device embodying the present invention,

Fig. 2 is a vertical sectional view taken on the line 2-2 of Fig. 3, and

Fig. 3 is a similar view taken on the line 3-3 of Fig. 2.

Referring to the preferred and illustrative embodiment of the invention as shown in Figs. 1, 2 and 3, it will be seen that a gas-heated device 1, which may take the form of a gas range, is provided with an outlet flue 2, through which the smoke and fumes may pass. This outlet opening is conveniently connected directly with a flue 3 which has been shown as a short oval shaped stove pipe section of sheet metal removably mounted on the adjacent portion of the gas range.

In accordance with the present invention, the upper end of the flue 3 is closed by means of a removable oval-shaped cap 4 having an annular-shaped walls formed of porcelain or other suitable ceramic material which shall be resistant to heat as well as the corrosive effect of the flue gases. This cap is provided with a horizontal top wall 5 and an outer, depending wall 6. The wall 6 extends down beyond the upper edge of the flue and snugly fits around an adjacent outer side portion 7 thereof.

The cap 4 is also provided with inwardly and downwardly sloping walls arranged to

form an annular re-entrant portion 8 which extends down into the upper end of the flue and is provided with a conical-like deflecting surface 9. The upper end of this surface merges into a curved, deflecting surface 10 on the under side of the cap 4. These surfaces assist in the deflection of the flue gases backwardly toward the center of the flue and along the conical-like surface 9.

Positioned directly under the re-entrant portion 8 of the cap 4, so as to receive the deflected gases, is a purifying chamber 11 which may take the form of a sheet metal cup. This cup preferably has a conical side wall 12 to decrease the back pressure on the gases flowing upwardly in the flue, and a short bottom wall 13. The upper edge of the side wall 12 conveniently projects up above the lower portion of the conical deflecting surface 9 and is spaced therefrom to provide an annular passage 14 for the deflecting of gases into the cup 11. The cup may be secured in this position in any convenient manner, as by riveting opposite sides to the adjacent portions of the flue side walls as indicated by numerals 15 and 16 respectively. The rivet 16 having an open center to provide an over flow opening 17 as hereinafter described.

It will be noted that the cup is so positioned that such foreign matter as is deposited on the conical surface 9 and the adjacent portion of the surface 10 moves by gravity into the cup 11, rather than back down the flue and into the gas range, thereby eliminating one source of disagreeable odors.

The purification of the flue gases is further assured by the provision of a purifying element in the cup 11. Preferably this takes the form of water. In this illustrated embodiment of my invention, I use a liquid purifying agent such as water. The gases flow along the surface of the water 11 and thus any foreign matter is removed from the gases and deposited in the cup.

The invention further contemplates means, whereby the purified gases may be conveniently discharged from the purifying cup 11. To this end, the outlet is provided in the central part of the re-entrant portion of the

cap 4. This passage leads from the central open space at the top of the cup just above the surface of the water, to the upper side 5 of the cap 4 and atmosphere. Conveniently, the sides of this outlet are frusto-conical in shape or flared outwardly as shown in the drawings to provide a maximum surface for the condensation of vapors and for directing the flue gases and any condensate into the chamber or cup 11.

10 In practice, the cup 12 is filled with water through this funnel shaped passage without removing the cap 4. The proper amount of water may be gauged in any convenient manner, as by observing the same through the 15 overflow opening 17. For simplicity in manufacture, this opening is formed by using a tubular rivet 16, when securing the cup 12 to the flue 3, as heretofore described and shown in the drawings. This gauge 20 opening serves as an overflow opening, tending to prevent the water from overflowing from the cup down into the flue 3 and the gas range, should an excessive amount be supplied to the cup 11.

25 In operation, the gases flow from the oven 1 up the flue 3 as indicated by the arrows and are deflected by the surfaces 9 and 10 into the filtering cup 11. The foreign matter deposited at this time on the surfaces 9 and 30 10 moves by gravity over these surfaces into the cup 11, where it is collected. The gases, in passing over the surface of the water, are further purified of grease, soot and other 35 undesirable material, which also collects in the cup 11. At the same time, the gases are supplied with moisture from the water in the cup which further purifies them in passing through the flue. The gases thus 40 purified and humidified then escape to atmosphere and through the outlet passage in the top of the cap. By thus providing the metallic flue pipe with a cap of porcelain material, any danger of the cap and the walls 45 of the flue pipe becoming corroded together is eliminated and these parts may be readily separated whenever it is necessary to clean the filter cup or otherwise inspect the flue for any reason.

50 The invention further contemplates a safety means for preventing the accidental closure of the outlet from the cup as would occur, for example, by placing a book, pan or other flat object over the same. This 55 safety means may conveniently take the form of a raised shoulder or rib 20, which projects above the upper side 5 of the cap 4 as illustrated in the drawings. Thus, with this rib on the cap, it is impossible to accidentally close the outlet opening of the passage by placing any flat object over the same.

60 The invention may be variously modified and embodied within the scope of the subjoined claims; for example, the water level

may be raised to the position indicated by the line B—B, Fig. 2. The gases now must pass through the water in the cup 11 before being discharged through the central outlet passage in the cap. Such change in the water level would, of course, necessitate a corresponding change in the position of the gauge opening 17.

70 While I have shown and described a liquid as the purifying and filter medium, it is obvious that the cup or receptacle 11 may be adapted to contain any other form of purifying material.

75 What I claim is:

1. In an oval-shaped device of the character described, a flue, a circular shaped receptacle adapted to contain a purifying element positioned within said flue and rigidly secured to the side walls thereof, and means operatively associated with said flue and 80 said receptacle adapted to deflect into said receptacle gases traversing said flue.

2. In a device of the character described, a flue, a purifying chamber, means having inner depending walls adapted to deflect the 85 gases from said flue into said chamber, said walls sloping downwardly and inwardly with respect to said chamber walls so that any condensation on the said depending walls shall move, under the force of gravity, 90 into said chamber, and an outlet for said chamber formed by the depending walls whereby the gases in said chamber may escape therefrom.

95 3. In a device of the character described, a flue, a chamber located within said flue, a means for securing the top of said chamber walls and said flue walls together, said means having an opening extending from said chamber through said flue wall to the 100 outside, and thereby providing a liquid level gauge for the chamber.

105 4. In a device of the character described, a flue, a purifying cup adapted to contain a liquid, means for securing said cup and said flue together, said means having an opening extending from said chamber through said flue walls, a cap for said flue having a portion adapted to deflect the gases traversing said flue into said cup, said cup 110 having an outlet opening for the purified gases, and a protective rib on said cap positioned adjacent to said outlet opening and extending beyond the same.

115 5. As a new article of manufacture, a deflector cap for gas flues and the like, comprising annular top walls of ceramic material, said walls arranged to support the cap on the flue walls, a central outlet having a flared opening formed by the inner portions 120 of said annular walls, and a projection formed in the top wall and at one side of the outlet.

125 6. As a new article of manufacture, a cap for a flue, comprising walls of ceramic mate- 130

rial including a top wall and inner and outer depending side walls, said outer wall being adapted to engage the flue walls, said inner wall sloping inwardly and downwardly to provide an inner surface for condensing vapors traversing the flue and directing condensate and gases into a receptacle, and a central outlet having a flared opening formed by said sloping walls.

10 7. As a new article of manufacture, a cap for a flue, comprising walls of ceramic material including a top wall and inner and outer depending side walls, said outer wall being adapted to engage the flue walls, said inner wall sloping inwardly and downwardly to provide an inner surface for condensing vapors traversing the flue and directing condensate and gases into a receptacle, a central outlet having a flared opening formed by

20 said sloping walls, and a projection formed in the top wall and at one side of the outlet.

25 8. As a new article of manufacture, an air conditioning device for gas ranges and the like, comprising a flue adapted to be attached on the flue vent of a gas range, a receptacle located within the flue and near the top portion thereof, portions of the side walls of said receptacle being positioned adjacent to the inside walls of said flue and se-
30 cured directly thereto, a closure cap for the flue, said cap having inside walls for engag-
ing the top of said flue walls, and depending walls sloping inwardly from said inside walls for deflecting gases and condensed va-
35 pors into said receptacle, and an outlet formed in the cap by the lower portions of said depending walls.

30 9. As a new article of manufacture, an oval-shaped flue, comprising a conical shaped receptacle located within said flue and having its top portion secured directly to the flue walls on the minor axis of said oval flue, and a closure cap for said flue hav-
40 ing wall members sloping downwardly and inwardly from the top of said cap to form a central opening whereby gases traversing the flue are deflected into the receptacle and then discharged through the opening.

40 10. In a device of the character described, an oval-shaped flue, a conical shaped receptacle located within said flue, the upper walls of said chamber forming a cylindrical top portion for said receptacle, the sides of which engage the walls of said flue on the 50 minor axis thereof, and means for rigidly securing the engaging portions of said receptacle and flue walls together.

50 11. In a device of the character described, an oval-shaped flue, a conical shaped cham-
60 ber located within said flue, the upper walls of said chamber engaging the walls of said flue on the minor axis thereof, means for rigidly securing the engaging portions of said chamber and flue walls together, and an overflow opening extending through the

walls of said flue and said chamber for con-
ducting any excess liquid from the chamber.

12. In a device of the character described, the combination with a metallic flue vent of a gas range, of a cap for said flue com-
70 prising walls of ceramic material including a top wall and inner and outer depending side walls, said outer wall being adapted to engage the flue walls, said inner wall sloping inwardly and downwardly to provide an inner surface for condensing vapors trav-
75 ersing the flue and directing the same into a receptacle, and central outlet having a flared opening formed by said sloping walls.

13. In a device of the character described, the combination with a metallic flue vent of a gas range, of a cap for said flue comprising walls of ceramic material including a top wall and inner and outer depending side walls, said outer wall being adapted to en-
80 gage the flue walls, said inner wall sloping inwardly and downwardly to provide an inner surface for condensing and deflecting vapors traversing the flue, a central outlet having a flared opening formed by said slop-
85 ing walls and a purifying means operative-
ly associated with said opening for intercepting gases and vapors escaping from said outlet.

80 90 In testimony whereof I affix my signature. 95
